Primary Examiner — Martie K Holtje(74) *Attorney, Agent, or Firm* — Salter & Michaelson(57) **CLAIM**

The ornamental design for a watch face, as shown and described.

DESCRIPTION

FIG. 1 is a perspective view of a watch face;
FIG. 2 is a plan view thereof; and,
FIG. 3 is a cross-sectional view thereof, taken in the direction of arrows 3-3 in FIG. 2.

The broken lines shown in the drawing views are included for the purpose of showing environmental structure that forms no part of the claimed design.
